(57) **CLAIM**

The ornamental design for a baby harness with a carrying strap, as shown and described.

DESCRIPTION

FIG. 1 is a front elevational view of a baby harness in an assembled state, without a carrying strap, according to my new design;

FIG. 2 is a rear elevational view of the baby harness of FIG. 1, which illustrates the loops to which the carrying strap of FIGS. 10-16 attaches;

FIG. 3 is a perspective view of the baby harness in an open position, without the carrying strap;

FIG. 4 is a rear elevational view of the baby harness of FIG. 3;

FIG. 5 is a front elevational view of the baby harness of FIG. 3;

FIG. 6 is a top plan view of the baby harness of FIG. 3;

FIG. 7 is a bottom plan view of the baby harness of FIG. 3;

FIG. 8 is a left-side elevational view of the baby harness of FIG. 3;

FIG. 9 is a right-side elevational view of the baby harness of FIG. 3;

FIG. 10 is a perspective view of the carrying strap, without the baby harness;

FIG. 11 is a front elevational view of the carrying strap of FIG. 10;

FIG. 12 is a rear elevational view of the carrying strap of FIG. 10;

FIG. 13 is a top plan view of the carrying strap of FIG. 10;

FIG. 14 is a bottom plan view of the carrying strap of FIG. 10;

FIG. 15 is a left-side elevational view of the carrying strap of FIG. 10; and,

FIG. 16 is a right-side elevational view of the carrying strap of FIG. 10.

The claim is directed to the appearance of the baby harness with the carrying strap. The harness and carrying strap are shown separately in the figures, for the purpose of showing aspects of the design that are not apparent from the other views.
